DRIVE CARDS - ONE OF EACH

HILL CARDS (MERIT CARDS) ONE OF EACH

BRIDGE CARDS (MERIT CARDS) ONE OF EACH

SPEED CARDS (COUNTED WITH MILEAGE CARDS) ONE OF EACH

MILEAGE CARDS - SIX OF EACH

UNITED STATES PATENT OFFICE.

WILLIAM E. WRISBERG, OF ST. LOUIS, MISSOURI.

PLAYING-CARDS.

1,373,286.

Specification of Letters Patent. Patented Mar. 29, 1921.

Application filed June 11, 1920. Serial No. 388,382.

To all whom it may concern:

Be it known that I, WILLIAM E. WRISBERG, a citizen of the United States of America, a resident of the city of St. Louis, 5 in the State of Missouri, have invented certain new and useful Improvements in Playing-Cards, of which the following is a full, clear, and exact description, reference being had to the accompanying drawings, 10 forming a part of this specification.

This invention relates to card games and particularly to a new deck of cards for playing an interesting game in which several 15 series of cards bearing different designations are employed to simulate and fix the record and score of an automobile tour.

In the drawings A represents a "drive suit" composed of six "drive cards," each 20 card of which is provided with a representation of a means of travel, the lowest card in value (No. 1) picturing a donkey, the next higher (Auto. No. 2) picturing a small four cylinder automobile, the next higher (Auto. No. 3) a large four cylinder automobile, the next higher (Auto. No. 4) a six cylinder automobile, the next higher (Auto. No. 5) an eight cylinder automobile and the highest (Auto. No. 6) a twelve cylinder automobile. The names of the automobiles 25 pictured may be either fanciful, such as Euclid, Laclede, Chouteau, Lindell and Delmar, or they may be named after standard makes of cars, as desired.

B represents the "hill suit" composed of 30 six "hill cards," each of which is provided with a representation of a hill and roadway, the lowest card of the suit picturing a mountain trail and the remaining cards picturing hills of increasing steepness, and numbered 40 from Hill II up to Hill VI.

C represents the "bridge suit" composed of six "bridge cards," each of which is provided with a representation of a channel or waterway, the lowest card picturing a ditch 45 and the remaining cards each picturing bridges of increasing strength and numbered from Bridge II to Bridge VI.

D represents the "speed suit" composed of six "speed cards," each of which is provided 50 with a speed indication thereon, and a flag or sign post, the speed indications being of increasing order as 35, 40, 45, 50, 55 and 60 miles per hour.

E represents the "mileage suit," composed 55 of thirty-six cards, there being six cards of each mileage designation, viz., six cards of

one mile, six cards of two miles, and so on up to six cards of six miles.

It will be understood that the other half of each card shown in the drawings may be 60 a duplicate of the representations shown in the upper half of the card, just as in an ordinary deck.

The six drive cards may have backs different in design, color or shade than the rest of 65 the deck so as to easily distinguish them when dealing, for they are dealt in a manner different than the dealing of the rest of the deck.

At the beginning of the game each player 70 receives only one of the drive cards, and retains this card with its face exposed on the table throughout the entire hand. This drive card has some bearing on the value of other cards held by the player.

The remaining cards have different values 75 which are counted after all the cards have been played, each player being given credit for the cards caught by him while the game is in progress.

The game may be played by three, four, 80 five or six players as desired, six being the preferable number. When six persons play, the entire deck is used. When five play, the highest card of each suit is discarded, 85 namely, Automobile No. 6, Hill No. VI, Bridge No. VI, 60 miles per hour and the six six-mile cards.

When four persons play, the drive cards 5 and 6, the hill cards V and VI, the bridge 90 cards V and VI, the speed cards 55 and 60 miles per hour and the mileage cards, 5 and 6 miles, are discarded.

When three persons play, the following are discarded in addition to the above: 95 Automobile No. 4, Hill No. IV, Bridge No. IV, Speed 50 and six of the four-mile cards.

Each player is called a driver, each deal a drive and the game is called a tour. When six persons play, six deals constitute 100 a tour, thus giving each person one deal. When five or four persons play 5 or 4 deals respectively constitute a tour, each player getting one deal. When three persons play, each player is given two deals and thus six 105 deals constitute a complete tour.

Dealing.—The first dealer is chosen by drawing, and is called the pilot, the pilot being the person who has drawn the donkey card. Thereafter, the cards are successively 110 dealt or "piloted" by the different players. The pilot deals the drive cards first, placing

- or "parking" one of them face down in front of each player or driver who will immediately turn them face up, leaving them in that position throughout the game, for they 5 designate the value of some of the remaining cards dealt each driver. The dealer then deals nine cards to each driver, face down, these cards being dealt preferably three at a time and from left to right.
- 10 Should the donkey driver be dealt speed cards in the deal, he must auction them off, one at a time, for a mileage or merit card before the play or tour begins, naming the speed card and calling for bids, starting 15 with the driver at his left. The dealer or pilot leads off in the game.

- Any driver other than a donkey driver holding the bridge or hill card (called "merit cards") having the same number as 20 his drive card is by such cards vested with the authority to "arrest speeders," those two cards thereby becoming "authoritative arrest cards" which take any trick in which a speed card is played by an adversary.
- 25 When a merit card becomes an authoritative arrest card it automatically becomes of greater value than other merit cards even though they may be of a higher number, for example, if the driver of auto No. 4 arrests 30 a speed card by playing Bridge No. IV or Hill No. IV, the driver of auto No. 3 cannot take the trick by playing Hill No. V or Bridge No. V. There may be one or more "arrests" in one trick, because the highest 35 authoritative arrest card takes the trick regardless of which may be played first.
- It is immaterial whether or not the authoritative arrest card is played before or after the speed card, for it is just as effective 40 either way. The drive cards are never played during the game but are only dealt to the players to show the relative value of some of their remaining cards.
- 45 *Value of cards to their respective players to win "drives" or tricks.*

- Speed and mileage cards are of increasing value in their ascending order (note that the donkey driver cannot hold speed cards).
- 50 The values of merit cards when held by the several players may be remembered by bearing in mind that the drive cards represent a donkey and automobiles of different weights and different degrees of power, auto No. 2 being a small light four cylinder car which is light enough to safely cross all of the bridges including the relative weak bridge II, but this small auto No. 2 is not powerful enough to climb any of the hills excepting 55 hill II. Auto No. 3 is too heavy to cross bridge II, but can safely cross any of the stronger bridges III, IV, V or VI, and it is powerful enough to climb hills II and III, although it cannot climb the relatively steep 60 hills IV, V and VI. Auto No. 4 can climb 65

hills II, III and IV, but it is too heavy to cross bridges II and III. Each auto is thus limited either by weight or power, or both weight and power. Further, the autos cannot cross the ditch nor climb the trail.

With the foregoing as a basis, the "merit cards" have different values in winning tricks, and in any particular case, the value of a "merit card" depends mainly upon its relation to the "drive card" held by the 70 player. All hill cards (except the trail) lower in number than the drive card held by a player and all bridge cards higher in number than the drive card are of increasing value as the numbers on the cards ascend. 75 For instance in considering auto driver No. 4, the merit cards will have the following order of value to him:

Hill card No. IV
Bridge card No. IV

of equal value and are authoritative arrest cards and take any speed card played by an adversary.

Bridge card No. VI.
Bridge card No. V.
Hill card No. III.
Hill card No. II.

Cards of no value to driver of auto No. 4:
Trail card No. I.
Ditch card No. I.
Bridge card Nos. III and II.
Hill card Nos. V and VI.

The donkey driver can play with effect only two merit cards of value, viz., the trail 100 card and ditch card. All the other merit cards are of no value to him and he cannot arrest for speeding nor hold speed cards.

If two cards of equal value are played, the first one played takes the trick.

Scoring.—Each player is given credit for cards caught by him. The object of the game is to make as much mileage and to win as many merits as possible. The mileage cards score as many miles as the cards 105 specify and the speed cards are counted with the mileage cards, scoring as many miles as they indicate miles per hour. All the merit cards (hill and bridge cards including ditch and trail cards) score as many 110 merits as the number designated on the cards. For instance, the card Hill No. IV counts four merits and the card Speed 40 miles per hour counts forty miles. Each deal or drive, when six persons play, totals 115 411 miles and 42 merits; when five persons play 315 miles and 32 merits, etc.

It will be understood that many modifications of the rules for playing the game may be resorted to without in any way departing from the invention.

I claim:

1. A deck of playing cards comprising a series of drive cards indicating types of traveling means, a series of merit cards in-

dicating different parts of a way to be traveled, a series of speed cards indicating speed of travel and a series of mileage cards indicating distances traveled, the relation 5 of the merit cards to the drive cards determining the value of the merit cards.

2. A deck of playing cards comprising a series of drive cards indicating types of traveling means including automobiles and 10 a donkey, a series of merit cards indicating different parts of a way to be traveled, said merit cards being composed of an equal number of hill and bridge cards, said 15 hill and bridge cards including a trail and ditch card, a series of speed cards indicating speed of travel, and a series of mileage cards indicating distances traveled.

3. A deck of playing cards comprising a series of drive cards and including a donkey 20 card and a plurality of automobile cards, a series of hill cards bearing designations of different inclined roadways thereon and including a trail card and a plurality of hill cards, a series of bridge cards bearing designations 25 of ways to be traveled and including a ditch card and a plurality of bridge cards representing different bridges, a series of speed cards bearing a plurality of increasingly numbered speed designations 30 thereon, and a series of mileage cards bearing designations of miles traveled and including a plurality of increasingly num-

bered mileage designations, there being one each of the drive, hill, bridge and speed cards and a plurality of the mileage cards 35 having the same value.

4. A deck of playing cards representing an automobile tour and comprising drive cards indicating different means of travel, a series of said drive cards having representations 40 of different automobiles thereon and another of said drive cards having a designation of an animal thereon, a series of hill cards having representations of different hills each corresponding to one of the drive 45 cards, bridge cards including a series of cards representing different bridges corresponding to the different automobiles on the drive cards and an additional card corresponding to the animal of the drive cards, a 50 series of different speed cards indicating speed of travel, and a series of different mileage cards indicating distances traveled.

5. In a deck of cards representing an automobile tour, the combination of a series 55 of drive cards, representing automobiles in which the respective players travel, a series of cards representing different parts of a way to be traveled by the automobiles, and a series of cards indicating different distances.

In testimony that I claim the foregoing I hereunto affix my signature.

WILLIAM E. WRISBERG.
